UNITED STATES PATENT OFFICE.

A. WELLS CASE, OF SOUTH MANCHESTER, CONNECTICUT.

CAR-CO尤LING.

SPECIFICATION forming part of Letters Patent No. 278,880, dated June 5, 1883.

Application filed March 7, 1883. (No model.)

To all whom it may concern:

Be it known that I, A. WELLS CASE, of South Manchester, in the county of Hartford and State of Connecticut, have invented a new and useful Improvement in Automatic Car-Couplings, of which the following is a full, clear, and exact description.

Reference is to be had to the accompanying drawings, forming a part of this specification, in which similar letters of reference indicate corresponding parts in all the figures.

Figure 1 is a side elevation, partly in section, of my improvement uncoupled. Fig. 2 is a side elevation of the same coupled. Fig. 15 3 is a front elevation of one coupling-head. Fig. 4 is a plan view of the two coupling-heads uncoupled.

The object of this invention is to promote convenience and security in the use of car-20 couplings.

The invention consists in a car-coupling constructed with coupling-heads having their sides beveled to adapt them to overlap each other, and in unequal-armed U-shaped coupling-rods 25 having curved bars attached to the ends of their long arms, to adapt the said rods to be turned to couple the cars by the coupling-head of an adjacent car when the cars are run together, as will be hereinafter fully described.

30 A represents the heads of the coupling, each of which is made with one or more mouths. The sides of the coupling-heads A are beveled, as shown in Fig. 4, leaving the forward parts of the said sides open, as shown in Figs. 1 and 2, 35 the remaining or rear parts of the said sides serving as guides to center the coupling-heads upon each other. With this construction, when two cars are run together, the upper part of the coupling-head A of the lower car will pass 40 between the upper and lower parts of the coupling-head A of the higher car, the cutting away of the sides of the coupling-heads allowing the said upper and lower parts to overlap sufficiently to bring the pin-holes B into line 45 with each other, as shown in Fig. 2.

C are the coupling-rods, which are bent into U shape, with one arm so much longer than the other as to pass through the coupling-heads A, while the ends of the short arms rest 50 upon the upper sides of the said coupling-heads, as shown in Figs. 1, 2, and 3.

To the lower ends of the long arms of the

coupling-rods C are rigidly attached the ends of curved bars D, which project about at right angles with the planes of the said coupling-rods, as shown in dotted lines in Fig. 4, the convex sides of the said curved bars D being 55 toward the short arms of the said rods C.

In the upper sides of the coupling-heads A are formed grooves E F, to receive the ends of 60 the short arms of the coupling-rods C, and which are curved in the arcs of circles having their centers in the axes of the long arms of the said coupling-rods. The curved grooves E terminate at the pin-holes B, so that the 65 ends of the short arms of the coupling-rods, when moving along the said grooves E, will readily pass into the said coupling-holes. The curved grooves F terminate in a shoulder at the side of the coupling-holes B, so that the 70 short arms of the coupling-rods C, when their ends are resting in the said grooves F, will not be liable to be jarred into the coupling-holes B. With this construction, when the cars are 75 to be coupled, the coupling-rods C are raised and the ends of their short arms are placed in the grooves E, which brings the curved bars D into the position shown in Fig. 4, so that when the cars are run together the lower jaw of the lower coupling-head A will strike the 80 curved bar D of the higher coupling-head A and push it back, turning the coupling-rod C upon its long arm as a pivot and swinging the short arm of the said rod forward. As the short arm of the coupling-rod C comes to 85 the hole B it drops through the said hole and couples the cars.

When the cars are to be run together without coupling, the coupling-rods C, when raised, are turned in such a direction that the ends of 90 their short arms will rest in the grooves F, which brings the curved bars D into a rearward position, so that they will not be struck by the jaws of the coupling-heads when the cars are run together.

95 When it is desirable to uncouple the cars from their tops, the ends of chains G are attached to the bends of the rods C at points directly over or near their short arms, as shown in Figs. 1, 2, 3, and 4. The other ends of the 100 chains G are secured to the tops of the cars. With this construction, when the chains G are pulled upon, the coupling-rods C will be raised, withdrawing their short arms from the holes

B, and then swinging the said rods C around upon their long arms, so as to bring the points of the said short arms over the grooves E or F, according to the direction in which the said chains are drawn.

Having thus described my invention, I claim as new and desire to secure by Letters Patent—

1. A car-coupling constructed substantially as herein shown and described, and consisting of the coupling-heads having beveled sides, and the unequal-armed U-shaped coupling-
10 rods C, having curved bars D, attached to the ends of their long arms, as set forth.

2. In a car-coupling, the coupling-
15 rods C, made, substantially as herein shown and de-
scribed, with unequal arms, and with curved
bars D, attached to the ends of their long arms,
to adapt the said rods to be turned to couple
the cars by the coupling-head of an adjacent
car, as set forth.

A. WELLS CASE.
